DESIGN FOR A SPECTACLE FRAME

Eric Barrett and Altina Barrett,
Beverly Hills, Calif.

Application February 24, 1945, Serial No. 118,125

Term of patent 14 years

(Cl. D57—1)

To all whom it may concern:

Be it known that we, Altina Barrett and Eric Barrett, citizens of the United States, residing at Beverly Hills, in the county of Los Angeles and State of California, have invented a new, original, and ornamental Design for a Spectacle Frame, of which the following is a specification, reference being had to the accompanying drawing, forming part thereof.

In the drawing,

Fig. 1 is a top view of a spectacle frame showing our new design;

Fig. 2 is a side view from the left of the spectacle temple piece shown in Fig. 1; and

Fig. 3 is a view of the right side thereof.

This is a division of application D-115,974, filed October 25, 1944.

The essential features of our design for a spectacle frame reside in the portions shown in full lines, and the same are characterized by a progressive widening of the bow or temple piece near the frame to provide a downwardly curving pointed lower portion.

We claim:

The ornamental design for a spectacle frame, substantially as shown and described.

ERIC BARRETT.
ALTINA BARRETT.
